UNITED STATES PATENT OFFICE.

GEORGE P. MCENTIRE, OF TOPEKA, KANSAS.

COVERING FOR MATTRESSES AND THE LIKE.

Application filed June 4, 1920. Serial No. 286,558.

To all whom it may concern:

Be it known that I, GEORGE P. MCENTIRE, a citizen of the United States, residing at Topeka, in the county of Shawnee and State 5 of Kansas, have invented certain new and useful Improvements in Coverings for Mattresses and the like, of which the following is a specification.

This invention relates to an improvement 10 in coverings for articles such as mattresses, cushions, and the like, and the primary object of the invention is to provide a covering for such an article having a distinctive strip or stripe associated therewith and so arranged 15 as to be in proximity to one or more edges of such article when the covering is applied thereto whereby the appearance of the article will be greatly improved at very slight extra expense and whereby the article 20 will have individuality and may be easily recognized and distinguished amongst a lot of such articles not so covered.

The invention consists in the novel constructions and arrangements to be herein- 25 after described and claimed for carrying out the above mentioned object as will appear from the following description of a preferred embodiment illustrated in the accom- 30 panying drawing wherein,

Fig. 1 is a perspective view of a covering embodying the principles of my invention as applied to a mattress having roll edges.

Fig. 2 is an enlarged fragmentary sectional view of the mattress before the roll 35 edges are formed.

Fig. 3 is a similar view of the same after the roll edges have been formed, and

Fig. 4 is a side elevation of a fragmentary portion of one of the roll edges.

Like characters of reference designate like parts in the several views.

The covering for the top 5, bottom 6, and side and end boxings 7 and 8, respectively, of the mattress may be made of any suitable material, for example, ticking which may be 45 of any desirable pattern or color. In the form of mattress illustrated in the drawings one or more of the edges, preferably all those running horizontally are covered with strips 9 and 10 of distinctive material. These 50 strips preferably form an inherent part of the covering, the strip 9 extending around the mattress and having its sides attached, respectively, to the top piece 5 and the side and end boxings 7 and 8, and the strip 10 55 also extending around the mattress and having its sides attached, respectively, to the side and end boxings 7 and 8 and the bottom piece 6. The roll edges are then formed by methods well known to those skilled in the 60 art and the distinctive strips 9 and 10 brought around the same as shown in Fig. 3. The roll is held in shape and the covering secured thereto by lacing twine 11 back and forth under the roll as shown in Figs. 3 and 65 4, the seams 12, 12, thereby being drawn in under the roll and hidden from sight.

I claim:

A mattress consisting of a tick and a filling, and formed with rolled edges, the tick 70 comprising top and bottom coverings, side and end boxings and strips sewed to said coverings and boxings to constitute the coverings for said rolls, the latter being formed by lacings extending through the filling and 75 through the seams between said strips and said top and bottom coverings and boxings whereby the seams are drawn under the rolls.

GEO. P. MCENTIRE.
